UNITED STATES PATENT OFFICE.

JOHN F. MALONE, OF BEMENT, ILLINOIS.

DESIGN FOR A TIRE-SETTING DEVICE.

SPECIFICATION forming part of Design No. 32,925, dated July 10, 1900.

Application filed May 28, 1900. Serial No. 18,330. Term of patent 7 years.

To all whom it may concern:

Be it known that I, JOHN F. MALONE, of the town of Bement, in the county of Piatt and State of Illinois, have invented and produced a new and original Design for a Tire-Setting Device, of which the following is a specification.

In the drawings forming part of this specification two sides and the top of my appliance are shown in isometrical perspective in Figure 1, and the two opposite sides are shown in Fig. 2.

The device is in the general form of a cube, with an extension from the center of its bottom or lower face. The extension, which is designated by reference-numeral 13, is square in cross-section, is longer than it is wide, and its sides are parallel with the sides of the cube-formed body from which it extends.

In addition to the generally-cubical form of the body and the correlation of the square extension therefrom the material features of the design reside in indentations in and configurations of the faces and top of the body, as follows: Face 1 has a recessed surface 2 extending from side to side. The indentation begins above the lower edge of the body, curves gradually into the body, and forms a groove 6 in the upper part of the body. The upper wall of the indentation 2 is at right angles with face 1, and the groove 6 is in the upper wall of the indentation parallel with the face 1 of the body. The face 3 has a groove 5 extending obliquely from side to side, and a corner is cut away on the side op-

posite face 1 from the top down to groove 5. The groove 5 is below the upper wall of indentation 2. It extends into the body at right angles with face 3, and it is highest next to face 1. The cut-away corner leaves a rectangular internal angle the vertical walls of which are shown at 4 and 14, and a vertical hole 15 extends through the intact lower corner. Face 9 has a vertical slot 10 set into its surface at right angles therewith. This slot 45 is near face 1 and parallel therewith. Face 11 shows an indentation 12 extending into the body at right angles with the face and at about the center thereof. A slot 8 cuts vertically through the top of the body and into 50 indentation 12. The slot is narrower than the indentation, and square shoulders are left where the slot and the indentation conjoin. The top of the body shows a rectangular recess 7 extending vertically into the body in 55 approximate alinement with slots 8 and 10. The internal angle 14 shows on the top of the body, as does also the slot 8.

Having described my invention, what I claim as new, and desire to secure by Letters 60 Patent, is—

The design for a tire-setting device, as herein shown and described.

In testimony whereof I sign my name in the presence of two subscribing witnesses.

JOHN F. MALONE
